(57) **CLAIM**

An ornamental design for a mobile carrier, as shown and described.

DESCRIPTION

FIG. 1 is an isometric view of a first embodiment of a mobile carrier, in accordance with the present invention;

FIG. 2 is a front elevation view of the first embodiment of the mobile carrier of FIG. 1;

FIG. 3 is a rear elevation view of the first embodiment of the mobile carrier of FIG. 1;

FIG. 4 is a left-side elevation view of the first embodiment of the mobile carrier of FIG. 1;

FIG. 5 is a right-side elevation view of the first embodiment of the mobile carrier of FIG. 1;

FIG. 6 is a top plan view of the first embodiment of the mobile carrier of FIG. 1;

FIG. 7 is a bottom plan view of the first embodiment of the mobile carrier of FIG. 1;

FIG. 8 is an isometric view of a second embodiment of a mobile carrier, in accordance with the present invention;

FIG. 9 is a front elevation view of the second embodiment of the mobile carrier of FIG. 8;

FIG. 10 is a rear elevation view of the second embodiment of the mobile carrier of FIG. 8;

FIG. 11 is a left-side elevation view of the second embodiment of the mobile carrier of FIG. 8;

FIG. 12 is a right-side elevation view of the second embodiment of the mobile carrier of FIG. 8;

FIG. 13 is a top plan view of the second embodiment of the mobile carrier of FIG. 8;

FIG. 14 is a bottom plan view of the second embodiment of the mobile carrier of FIG. 8.

FIG. 15 is an isometric view of a third embodiment of a mobile carrier, in accordance with the present invention;

FIG. 16 is a front elevation view of the third embodiment of the mobile carrier of FIG. 15;

FIG. 17 is a rear elevation view of the third embodiment of the mobile carrier of FIG. 15;

FIG. 18 is a left-side elevation view of the third embodiment of the mobile carrier of FIG. 15;

(Continued)

FIG. 19 is a right-side elevation view of the third embodiment of the mobile carrier of FIG. 15;

FIG. 20 is a top plan view of the third embodiment of the mobile carrier of FIG. 15; and,

FIG. 21 is a top plan view of the third embodiment of the mobile carrier of FIG. 15.

In the drawings, the broken lines illustrate portions of the mobile carrier that form no part of the claimed design.
